CLAIM

The ornamental design for a fire pit, as shown and described.

DESCRIPTION

FIG. 1 is an upper perspective view of a first embodiment of the fire pit showing my new design.

FIG. 2 is a front elevation view thereof.

FIG. 3 is a left side elevation view thereof.

FIG. 4 is a right side elevation view thereof.

FIG. 5 is a rear elevation view thereof.

FIG. 6 is an upper perspective view of a second embodiment of the fire pit showing my new design.

FIG. 7 is a front elevation view thereof.

FIG. 8 is a left side elevation view thereof.

FIG. 9 is a right side elevation view thereof; and,

FIG. 10 is a rear elevation view thereof.

The broken lines shown in the drawings are for purposes of illustrating portions of the article that form no part of the claimed design.

1 Claim, 10 Drawing Sheets
